UNITED STATES PATENT OFFICE.

CHARLES SCHLEI, OF BRILLION, WISCONSIN,

PIPE.

SPECIFICATION forming part of Letters Patent No. 471,775, dated March 29, 1892.

Application filed November 14, 1891. Serial No. 411,872. (No model.)

To all whom it may concern:

Be it known that I, CHARLES SCHLEI, a citizen of the United States, and a resident of Brillion, in the county of Calumet, and in the 5 State of Wisconsin, have invented certain new and useful Improvements in Pipes; and I do hereby declare that the following is a full, clear, and exact description thereof.

The object of my invention is to provide 10 stovepipe-sections having adjustable joints at one or both ends thereof, so that they can be very readily and firmly put together, and thereby do away with the difficulty heretofore experienced in connecting the sections 15 in the manner common to the art to which my invention relates.

My invention therefore consists in certain 20 peculiar and novel features of construction and arrangement of parts to be hereinafter described, with reference to the accompanying drawings, and subsequently claimed.

In the drawings, Figure 1 represents a side 25 elevation of the ends of two stovepipe-sections, one of the latter being provided with a joint constructed according to my invention; and Fig. 2, a section on line 2 2 of the preceding figure.

Referring by letter to the drawings, A B 30 represent the ends of two stovepipe-sections, the section A being seamed in the ordinary manner for a suitable distance of its length and then slotted circumferentially for a certain distance to form flaps a. The latter, instead of being formed with the ordinary 35 seam-folds, as is the case with the longitudinal edges of the remainder of said pipe-section, are left plain, so as to overlap each other.

Suitably secured to the flaps a, at a suitable 40 distance from the edges thereof, are ears b, connected by a screw-bolt c, having a nut d.

From the construction and arrangement of 45 parts above described it will be seen that in putting the two pipe-sections A B together one end of the latter pipe-section is inserted in the opposing end of the former section,

and then upon tightening the screw-bolt c the flaps a will be drawn together, to thereby clamp both pipe-sections in place, as shown in Fig. 1. When desired to remove the section B, the screw-bolt c is loosened, causing 50 the flaps a to relax and enabling said section B to be readily withdrawn from the opposing section.

Although I have shown and described the flaps a as being integral with the pipe-section A, it will be understood that the same may be suitably shaped and otherwise secured to said pipe-section without departure from the spirit of my invention. It will also be understood that, although I have shown 60 and described my joint in connection with stovepipes, it is equally as applicable to various other pipes.

Having thus described my invention, what 65 I claim as new, and desire to secure by Letters Patent, is—

1. A pipe-section provided with a circumferential slit through a portion of its periphery adjacent to the end thereof, the remainder of the pipe-section being seamed in the 70 ordinary manner, but the end portion being left free, with the seaming-edges thereof overlapping, ears attached to said free end portions, and a screw-bolt connecting said ears, substantially as set forth. 75

2. As an improved article of manufacture, a stovepipe-section seamed in the ordinary manner for a suitable distance of its length and then slotted circumferentially for a certain distance to form end flaps, ears secured 80 to the flaps, and a screw-bolt for engagement with the ears, substantially as set forth.

In testimony that I claim the foregoing I have hereunto set my hand, at Brillion, in the county of Calumet and State of Wisconsin, in 85 the presence of two witnesses.

CHARLES SCHLEI.

Witnesses:

M. THOMSEN,
WM. SCHLEI.
